UNITED STATES PATENT OFFICE

2,575,888

RAILWAY CAR TRUCK BOLSTER

Claude L. Orr, Columbus, Ohio, assignor to The
Buckeye Steel Castings Company, Columbus,
Ohio

Application December 7, 1944, Serial No. 566,988

3 Claims. (Cl. 105—229)

1

This invention relates to improvements in railway car trucks and more particularly to a novel bolster for such trucks.

The primary object of the invention is to provide a bolster structure for six wheel trucks, or the like, and including in a single integral metal casting, parts of the bolster system which have heretofore been made generally in three pieces, namely a center bolster and two transverse bolsters.

Another object is to reduce the weight of such a bolster system by eliminating the overlapping parts of the center and transverse bolsters and by taking advantage of other economies in weight made possible by the novel integral construction.

A further object is to simplify the manufacture of the bolster ensemble by reducing the number of parts to be handled, and by the elimination of machine work required on the three-piece system at the points where they bear upon each other.

Still another object is to produce a one-piece bolster having spring bearing surfaces which will remain at all times in fixed predetermined relationship with each other and the center plate surface, particularly with regard to squareness and the horizontal plane of the bearing surfaces.

Although the invention is particularly adapted for six wheel trucks, it is equally suitable for application to trucks having a greater number of wheels, as for example, an eight wheel truck. The invention is hereinafter described in connection with a six wheel truck and is illustrated in the accompanying drawings in which:

Fig. 1 is a top plan view of a railway car truck provided with one form of the improved bolster and with certain parts broken away and with others omitted to facilitate illustration.

Fig. 2 is a side elevation.

Fig. 3 is a longitudinal vertical sectional view on the line 3—3 of Fig. 1.

Fig. 4 is a transverse vertical sectional view on the line 4—4 of Fig. 1.

Fig. 5 is an enlarged top plan view of one form of the bolster, partially broken away.

Fig. 6 is a side elevation of the same.

Fig. 7 is a vertical longitudinal sectional view on the line 7—7 of Fig. 5.

Figs. 8 and 9 are vertical sectional views, respectively, of details on the lines 8—8 and 9—9, respectively, of Fig. 5.

Fig. 10 is an end elevation partly in transverse vertical section, the section being taken on the line 10—10 of Fig. 5.

2

Fig. 11 is a vertical sectional view of a detail on the line 11—11 of Fig. 5.

Fig. 12 is a fragmentary top plan view of a modification.

- 5 Referring to Figs. 1 to 4, inclusive, 13 designates the wheels of a six wheel car truck, which wheels support end axles 14 and an intermediate axle 15. The axles support the side frame systems 16 comprising side frames 16a journaled on the ends of the end axles 14 and overlapping at their inner ends. The inner ends are pivotally connected at 16b to oppositely extending arms of equalizer members 16c rotatably mounted upon the ends of the intermediate axle 15. The side frames 16a have bolster openings 17 for the accommodation of spring groups 18 which support the ends 19 of arms 20 of my improved bolster 21, each arm having inner and outer lugs 22 and 23 which slidably engage the bolster guide columns 24 of the side frames.

10 It may be seen from Figs. 1 and 5 that the bolster is generally H-shaped in plan with the legs 25 extending transversely of the truck and resting at their ends upon the springs 18 which, in turn, rest upon the spring seats 26 of the side frames. It will be evident that the H-shape is well adapted in use for trucks of this type, because it provides space between the legs 25 for the center wheels 13 and their associated brake parts, while at the same time, the legs are narrow enough to pass between the center and end wheels without requiring an excessively long wheel base truck. This is, also, facilitated by arranging the arms 20 at the outer ends of the legs in diverging relation at each side of the truck.

15 The bolster, as shown in detail in Figs. 5 to 11, inclusive, comprises a central plate 27 provided at its top with a center bearing 28, these portions being supported by a transversely extending beam 29 having deep opposite side portions 30, and a more shallow central portion 31. Each part 30 extends transversely and is preferably provided with substantially parallel side walls 32, and the inner walls 32 are joined by an inverted U-shaped web 33 formed at the bottom of the part 31, so as to provide clearance for the medial axle 15 when the bolster is used on a six wheel truck. The beam 29 merges at its ends with longitudinal beams 34 having integral side bearing tables 35. At each end, the beams 34 merge with and are supported by the beams which form the legs 25. Each end of each leg 25 is shaped, as indicated at 36 in Fig. 6, to rest

on the springs 18. The beams 29, 30, and 34, as well as the beams forming the legs 25, are all preferably formed substantially as box sections.

A novel arrangement of internal ribbing is used at each point where beams 34 join the legs 25. The inner side walls of the beams forming said legs are omitted across the width of the beams 34 for manufacturing reasons. In order to compensate in the strength of the leg beams 25 for this discontinuity of side wall, a vertical rib 37 is provided in each beam 25 at each intersection with beams 34, and these ribs 37 are integral with the top and bottom of the beams 25 and are arranged substantially parallel to the side walls of the latter. A similar central rib 38 is provided partially in each beam 34 and partially in each beam 25 and extends to the outer wall of the latter where it merges into said wall, as indicated at 39. Each rib 37 intersects one of the ribs 38, as indicated at 40, to form a cross-shaped reinforcement within the bolster structure and each rib 38 connects the tops of the beams 34 and 25, to the bottoms thereof. Ribs 38 serve to carry a portion of the vertical load from the beams 34 to the outer side walls of the leg beams 25, thereby producing a more desirable loading of the latter than would otherwise be obtained without the use of such ribs.

Other vertical ribs 41 are provided in each arm 20 substantially midway between the side walls thereof, and these ribs are integral with the tops and bottoms of the arms.

The above described integral bolster structure provides ample space for the provision of brackets, such as 42 and 43, for application of brake parts in symmetrical arrangement so as to avoid twisting forces upon the bolster structure. Although not illustrated, the bolster is also adapted to the application of integral brackets for supporting cylinders of brake mechanism, where such applications are desired.

In the alternate construction shown in Fig. 12, the bolster is substantially X-shaped in plan view, and the central portion is similar to that described in connection with Figs. 5 to 11, inclusive, in that the central plate 44 supports a center bearing 45 and both are carried by a transverse beam having substantially parallel vertical walls 46. Beams 25 of the H-bolster, however, are eliminated, and four legs 47 are provided, having spring seats on the under sides of their outer ends and converging toward the center plate at their inner ends. The legs 47 merge with the longitudinally extending beams 48 and each leg is preferably provided with vertical ribbing 49 connecting its top and bottom and arranged substantially midway between the side walls or the like. The objects and advantages of this type of bolster are the same as those covered in detail for the H-shaped construction.

While I have disclosed what I now consider to be preferred embodiments of the invention in such manner that they may be readily understood by those skilled in the art, I am aware that changes may be made in the details disclosed without departing from the spirit of the invention, as expressed in the appended claims:

What I claim and desire to secure by Letters Patent is:

1. In a bolster for a railway car truck, a beam substantially box-shaped in section adapted to be arranged transversely of the truck including side walls and a top wall and a bottom wall, a beam extending longitudinally of the truck arranged substantially at right angles to the first

beam, said longitudinal beam being substantially box-shaped in section having side walls and a top wall and a bottom wall, the top wall of the longitudinal beam adjacent the transverse beam lying in the horizontal plane of the top wall of the transverse beam and integral therewith, the bottom wall of the longitudinal beam adjacent the transverse beam lying in the plane of the bottom wall of the transverse beam and integral therewith, one side wall of the transverse beam being omitted across the width of the longitudinal beam, one side wall of the longitudinal beam being arcuate shaped adjacent the transverse beam and merging integrally with one side wall of the transverse beam, the other side wall of the longitudinal beam being arcuate shaped adjacent the transverse beam and merging integral with the contiguous side wall of the transverse beam, a vertically disposed rib joining the top and bottom walls of the transverse beam extending lengthwise thereof across the width of the longitudinal beam inwardly from the side walls of the transverse beam, and a vertically disposed rib joining the top and bottom walls of the longitudinal beam intersecting the first rib and extending across the transverse beam joining the top and bottom walls thereof.

2. In a bolster for a railway car truck, a beam substantially box-shaped in section adapted to be arranged transversely of the truck including side walls and a top wall and a bottom wall, a beam extending longitudinally of the truck arranged substantially at right angles to the first beam, said longitudinal beam being substantially box-shaped in section having side walls and a top wall and a bottom wall, the top wall of the longitudinal beam adjacent the transverse beam lying in the horizontal plane of the top wall of the transverse beam and integral therewith, the bottom wall of the longitudinal beam adjacent the transverse beam lying in the plane of the bottom wall of the transverse beam and integral therewith, the bottom wall of the longitudinal beam adjacent the transverse beam lying in the plane of the bottom wall of the transverse beam and integral therewith, one side wall of the transverse beam being omitted across the width of the longitudinal beam, one side wall of the longitudinal beam being arcuate shaped adjacent the transverse beam and merging integrally with one side wall of the transverse beam, the other side wall of the longitudinal beam being arcuate shaped adjacent the transverse beam and merging integral with the contiguous side wall of the transverse beam, a vertically disposed rib joining the top and bottom walls of the transverse beam extending lengthwise thereof across the width of the longitudinal beam inwardly from the side walls of the transverse beam, a vertically disposed rib joining the top and bottom walls of the longitudinal beam intersecting the first rib and extending across the transverse beam joining the top and bottom walls thereof, and a rib joining the top and bottom walls of the transverse beam substantially midway between the side walls thereof.

3. In a bolster for a railway car truck, a beam substantially box-shaped in section adapted to be arranged transversely of the truck including side walls and a top wall and a bottom wall, a beam extending longitudinally of the truck arranged substantially at right angles to the first beam, said longitudinal beam being substantially box-shaped in section having side walls and a

top wall and a bottom wall, the top wall of the longitudinal beam adjacent the transverse beam lying in the horizontal plane of the top wall of the transverse beam and integral therewith, the bottom wall of the longitudinal beam adjacent the transverse beam lying in the plane of the bottom wall of the transverse beam and integral therewith, one side wall of the transverse beam being omitted across the width of the longitudinal beam, one side wall of the longitudinal beam adjacent the transverse beam merging integrally with one side wall of the transverse beam, the other side wall of the longitudinal beam contiguous with the transverse beam merging integral with the same side wall of the transverse beam, a vertically disposed rib joining the top and bottom walls of the transverse beam and extending across the width of the longitudinal beam substantially parallel to the side walls of the transverse beam, and a vertically disposed rib joining the top and bottom walls of the longitudinal beam intersecting the first rib and extending across the transverse beam joining the top and bottom walls thereof and merging with the remote side wall of the transverse beam.
